UNITED STATES PATENT OFFICE

143,394

DESIGN FOR A COMBINED POWER TAKE-OFF AND PULLEY DRIVE UNIT

Walter F. Benning, Toledo, Ohio, assignor to Willys-Overland Motors, Inc., Toledo, Ohio, a corporation of Delaware

Application November 18, 1944, Serial No. 116,442

Term of patent 14 years

(Cl. D55—1)

To all whom it may concern:

Be it known that I, Walter F. Benning, a citizen of the United States, residing at 3343 Aldringham Road, Toledo, county of Lucas, and State of Ohio, have invented a new, original, and ornamental Design for a Combined Power Take-Off and Pulley Drive Unit, of which the following is a specification, reference being had to the accompanying drawing, forming part thereof.

Figure 1 is a perspective view of a combined power take-off and pulley drive unit, showing my

new design with the pulley omitted for convenience of illustration;

Figure 2 is a top plan view of the complete unit; and

Figure 3 is a rear elevational view of Figure 2.

The dominant features of my design reside in the portions shown in full lines on the drawing.

I claim:

The ornamental design for a combined power take-off and pulley drive unit, substantially as shown and described.

WALTER F. BENNING.
